UNITED STATES PATENT OFFICE

ELBRIDGE G. MATTHEWS, OF OAKHAM, MASSACHUSETTS.

IMPROVEMENT IN EXTENSION-TABLES.

Specification forming part of Letters Patent No. 147,955, dated February 24, 1874; application filed January 3, 1874.

To all whom it may concern:

Be it known that I, ELBRIDGE G. MATTHEWS, of Oakham, in the county of Worcester and State of Massachusetts, have invented a new and valuable Improvement in Extension-Tables; and I do hereby declare that the following is a full, clear, and exact description of the construction and operation of the same, reference being had to the annexed drawings making a part of this specification, and to the letters and figures of reference marked thereon.

Figure 1 of the drawings is a representation of a plan view of my extension-table. Fig. 2 is a sectional view of the same.

This invention has relation to extension-tables; and it consists in the novel construction and arrangement of certain parts, as will be hereinafter explained.

The following is a description of my improvements:

The table-top shown in the annexed drawings consists of two rigid end sections, D D¹, and an intermediate section, D², which latter is composed of narrow transverse strips d, glued or otherwise secured upon a flexible sheet of canvas, or other suitable material. This folding section D² is secured by one end to the straight end of the longest rigid top section D, so as to move with it when the table is extended or shortened. The top section D is secured upon the supporting-frame A, and the top section D¹ is secured upon the supporting-frame B. The side rails of the frame A have long dovetail tenons a a on their outer sides, which are received by corresponding grooves a' made into the side rails of the frame B. This construction of the two supporting-frames unites them, and at the same time allows them to be extended and contracted without detach-

ment. The frame B has side wings or flanges C formed on or secured to its side rails, through which slots b² are made longitudinally, for receiving through them the handles b¹ of two slides, b. These slides are adjustable longitudinally, and are intended for supporting the folding section D², when the same is wholly or partly drawn out of its concave receiver E. G designates a winch-drum, having its end bearings in the side rails of the supporting-frame B, and carrying on one end a crank, h, for turning it. Around this drum G a rope, g, is wound, one end of which is secured to a transverse connecting-piece, A', of frame A, and the other end is secured to a transverse piece of the same frame.

By turning the winch G, and winding upon it one portion of the rope g, the supporting-frames A B will be extended, and with them the table top; and by reversing the winch G, the parts A B D D¹ D² will be shortened, and the folding portion of the top will be rolled up in the receiver E. When the table-top is extended, the folding portion D² will be supported partly by the frame B, and partly by the slides b.

What I claim as new, and desire to secure by Letters Patent, is—

In an extension-table, the combination of the slotted flanges C on the side rails B, and the slides b provided with handles b¹, with the folding section D², substantially as shown, and for the purposes specified.

In testimony that I claim the above I have hereunto subscribed my name in the presence of two witnesses.

ELBRIDGE G. MATTHEWS.
